UNITED STATES PATENT OFFICE.

DAVID MORLEY HEY, OF CHATTANOOGA, TENNESSEE, ASSIGNOR TO VACUUM DYEING MACHINE COMPANY, OF CHATTANOOGA, TENNESSEE, A CORPORATION OF TENNESSEE.

DYEING APPARATUS.

1,199,982.

Specification of Letters Patent.

Patented Oct. 3, 1916.

Application filed April 5, 1910. Serial No. 553,470.

To all whom it may concern:

Be it known that I, DAVID M. HEY, a citizen of the United States, residing at Chattanooga, in the county of Hamilton and 5 State of Tennessee, have invented new and useful Improvements in Dyeing Apparatus, of which the following is a specification.

This invention relates to bleaching and dyeing apparatus of the type in which the 10 material to be treated is held in bulk and under compression in a chamber whose opposite walls are formed by perforated plates and wherein the liquor is forced under pressure through said material, usually by means 15 of a centrifugal pump having suitable connection with liquor-receiving and overflow portions of the vat respectively: and the invention consists in certain peculiarities in the construction and arrangement of parts 20 and certain novel combinations of elements substantially as hereinafter described and particularly pointed out in the subjoined claims.

It may be stated in a general way that 25 practical experience with this type of dyeing apparatus, as hitherto proposed, has shown defects in respect of the uniform dyeing of the material subjected to treatment therein.

30 My present invention is designed to remove various contributing causes of such defects, first, by securing a better distribution of the dye liquor at the receiving portion of the dyeing vat, second by securing a more 35 uniform overflow of the dye liquor from the discharging portion thereof, third in effectively guarding against the possibility of the liquor flowing more rapidly along the side wall of the dye chamber than in other 40 parts, caused either by the force of suction, acting strongly at a place adjacent to the suction pipe and more weakly, if at all, at places remote therefrom, or by the tendency of the steam to collect near the bottom of 45 the vat and jet up along side the wall of the latter, or by both of these things.

One of the important features of the present invention is a novel construction of distributor, designed to secure a better distribution 50 of the dye liquor within the inlet space of the vat and hence reduce the tendency to a non-uniform supply of the liquor to the various parts of the interior of the dyeing chamber, said distributor also having as one

of its features provision for either a rapid 55 or a gentle inflow of the dye liquor to the dye chamber, as conditions require.

Another of the important features of the present invention is a novel form of overflow chamber designed particularly to secure 60 the benefits which arise from provision for the overflow of dye liquor entirely around the discharge side of the dyeing chamber, or substantially entirely around the same, without the disadvantages of the 65 double tank constructions which hitherto have contained such provision.

A third important feature of the present invention is the provision of means of simple and practicable character which will effectively prevent the dye liquor from entering 70 the dyeing chamber at a place alongside the wall of the latter.

A fourth important feature of the present invention is a novel construction of compression plate, particularly designed to be 75 fully capable of withstanding all the strains which can be imposed upon it in practice.

In a general way it may also be stated that the present distributor, the present 80 overflow chamber and the present means for excluding entrance of fluid into the dye chamber at the wall of the latter, coöperate in securing a uniform flow of the liquor through all parts of the dyeing chamber and 85 a uniform treatment of the material by the liquor, thereby producing important advantages in respect of the imparting of uniform color to the mass in the dyeing chamber, 90 which is an ultimate object of my invention.

In the accompanying drawings I have 95 illustrated a dyeing apparatus embodying what I now consider to be the best forms of the several features referred to. It is to be understood, however, that the invention is not restricted to the illustrated details, and may be embodied in many apparently widely different forms without departing from the spirit of the invention or the scope of the subjoined claims.

100 In the drawings: Figure 1 is a side elevation of a dyeing apparatus constructed in accordance with my invention, showing the compression plate elevated and the clamping devices removed. Fig. 2 is a vertical section 105 through the dye vat. Fig. 3 is a plan view of the compression plate. Fig. 4 is a plan view of the dye vat, with the perforated

false bottom partly broken away. Fig. 5 is a detail view of the member joining the distributor with the supply pipe, and Fig. 6 is a transverse section of one of the arms 5 of the distributor, looking toward the inlet end thereof.

The same characters of reference designate the same parts throughout the several views.

10 A dyeing machine embodying my present improvements comprehends a dye vat A, having a perforated compression plate 10 and a perforated false bottom 11, a pump B, supply pipe C and C', and return or suction pipe D, D', D'', whereby the liquor is circulated and caused to impregnate the material to be dyed, while it is compressed between the perforated plates 10 and 11 in the dye vat. The suction and return pipes are 20 preferably arranged so that the direction of flow of the dye-liquor may be reversed at will. To accomplish this the circulating system, as herein shown, includes a pipe C² arranged between the supply pipe C' and return pipe D² and having valves c, c', at its junction with each of said pipes, and pipes C³ and D³ leading from the supply pipe C' and return pipe D respectively and connected to each other by a pipe D⁴. Suitable 30 valves d, d', d'', are provided at the junctions of these pipes.

The dye vat A may be of any desired size and shape and has a vertical side wall 12 and a reinforced bottom 13 with a central 35 aperture 14 therein. It comprises a liquor-receiving space or chamber a, a dyeing space or chamber a' and a discharge space for chamber a² arranged one above the other, as illustrated in Fig. 2. It is provided with 40 a shoulder 15 between the chambers a and a' and this shoulder supports the bottom plate 11 hereinbefore referred to, said bottom plate having an imperforate outer portion 11^b which rests upon said shoulder, a depending flange 16 which extends downward 45 from the imperforate portion substantially to the bottom of the chamber a and a perforated section 11^a bounded by its said imperforate portion. I am aware that a bottom 50 plate of this form has been previously used and that it was supported on lugs projecting from the inner wall of the vat, but in the previous proposal referred to there was no thought of so co-relating the parts that 55 liquor will be positively excluded from flowing from the liquor-receiving chamber a into the dyeing chamber a' along the outer wall of the latter in order that the formation of channels along the outer wall of the mass 60 of material may be positively avoided, whereas this is essential according to this particular part of the present invention. This is best accomplished by forming the 65 part of the side wall of the vat which bounds the liquor receiving chamber a of greater

thickness than the part which bounds the dyeing chamber a', with an abrupt change from one to the other, whereby the shoulder 15 is formed at the junction of said chambers and whereby also the liquor-receiving chamber is of less internal diameter than the dyeing-chamber and has its wall disposed at all points within the line of the wall bounding the latter chamber, and by so arranging the flange 16 that its outer surface will be in proximity to the wall of the liquor receiving chamber throughout and its lower portion will be close to the bottom of said chamber, and by arranging the plate 11 so that its outer edge will be close to the inner surface of the wall of the dyeing chamber a'. The central perforated portion 11^a of the bottom plate may also be reinforced, as by depending flanges 17. Lifting chains 18 are secured to the false 85 bottom plate 11.

The upper or compression plate 10 is preferably of the same size and shape as the interior of the vat A and to resist the various strains imposed upon it may be reinforced, 90 preferably by radially disposed truss-shaped ribs 21 and spaced parallel webs 22. As herein shown, the perforated compression plate 10 is circular, and is provided with integral concentrically-disposed webs 22 95 gradually decreasing in height from the center to the edge of the plate. The outermost web 22 is disposed a short distance from the edge of the compression plate and is provided with an outwardly-extending 100 portion 23 of gradually reduced thickness, said portion reinforcing the edge of the plate and having pockets 25 cut therein at intervals to provide bearing surfaces for the clamps 26 to be hereinafter described. 105 Opposite each of these pockets the outermost web 22 is strengthened by inwardly-extending perforated braces 24, while between the pockets the web may be raised, as shown at 22^a in Fig. 1. The truss shaped ribs 21 are 110 disposed radially between the inner and outermost of the webs 22. Suitable openings 27 are provided in the reinforcing ribs or webs through which hooks or other suitable means attached to the hoist 28 may be 115 inserted when it is desired to remove the compression plate.

Encircling the dye vat at or near its upper extremity is a relatively shallow conduit arranged to receive the dye liquor from the 120 vat A, and is herein shown as an open overflow chamber 29 having an outer wall 30 extending to a point slightly above the top of the side wall of the vat A which forms the inner wall of the conduit, and an inclined bottom 31 sloping gradually toward one side of the conduit, which side is provided with an outlet 32, so that the dye-liquor, flowing toward this side of the chamber, will empty into the return or suction 130

pipe D, one end of which is threaded or otherwise suitably secured in the outlet 32. It is apparent that the specific construction of the conduits described, while advantageous, is not altogether essential; for example, the side wall of the vat may be apertured to allow the dye-liquor to enter the conduit without overflowing over the side of the vat, or the conduit may be discontinuous, or need not entirely encircle the dye-vat, while one or more discharge openings may be provided in the conduit suitably arranged and connected to return the liquor to the pump B. It is essential, however, that if the vat be apertured for the flow of liquor therefrom into the conduit, the apertures be such as not to restrict said flow to any material extent, it being important that a free overflow of the material from the discharge chamber be provided for; and further that if, in lieu of a continuous conduit, a plurality of conduits be employed these conduits must substantially encircle the upper portion of the vat, in order that the required free and even flow of the liquor from the discharge portion of the vat be not interfered with. In the normal operation, the dye-liquor is drawn through the suction pipe D by the pump B and is then returned to the dye-vat through the supply pipe C, entering the vat through the aperture 14 in the bottom 13 thereof, and issuing through the distributor 33.

A coupling member 34 having a conduit 35 therein is preferably interposed between the distributor and the supply pipe, said coupling member having a central outlet 36 adapted to be connected to the distributor 33 and an annular flange 34^a by which it is connected with the supply pipe C. This coupling member 34 is provided with a flange or plate 34^b of sufficient area to cover the aperture 14 and is suitably secured to the bottom of the vat. Said aperture 14 is of greater diameter than the head of the distributor.

The distributor 33 is preferably constructed with a hollow multi-lateral head 37 having an aperture 38 in each of its sides. It is preferably threaded to the outlet 36 of the coupling member 34. The upper face of the head 37 preferably is perforated, as at 39, to allow the dye-liquor to issue into the dye-vat near the center of the same. Connected to each side of the head 37 are radially-disposed hollow distributing arms 40, of rectangular or other suitable shape and having a perforated and a solid portion, the form herein shown having perforations 41 in all but one of its sides, (see Fig. 6) through which the dye-liquor issues. The hollow radially-disposed distributing arms extend to within a short distance of the side wall of the liquor receiving chamber a, and the dye-liquor issuing

through the perforations in these arms 40 and the central head 37 is uniformly supplied to the various portions of the interior of the dye-vat.

Any suitable means may be provided to connect the distributing arms 40 to the head 37, but these means are preferably of such nature that the arms 40 may be readily turned or detached and replaced in the same or a different position. In the form of the invention exemplified by the accompanying drawings this is provided for by securing the arms removably to the head by means of cap screws 40^a extending through apertures in flanges 40^b at the inner ends 80 of the arms. When the distributing arms 40 are secured in the position illustrated in Fig. 2, the imperforate side of each distributing arm faces the bottom of the vat and the dye liquor will jet through the perforations in the uppermost side of the distributing arms directly toward the perforated false bottom 11 and the material to be dyed. With certain goods or materials, however, it is advantageous to cause the dye-liquor to rise more gently against the material to be dyed, and it will be noted that by slackening the cap screws 40^a, turning the distributing arms 40 so that the imperforate side of each faces the material to be dyed, and securing the arms to the head in the last named position, the dye-liquor will issue through the perforations 41 in downward and lateral directions and contact with the bottom 13 of the vat before reaching the dyeing material.

In the operation of the machine, the material to be dyed is deposited upon the perforated false bottom plate 11 and is compressed between the same and the perforated upper compression plate 10, suitable clamps 26 being provided at the sides of the vat for retaining the compression plate in position. The dye-liquor is forced by the pump B through the supply pipe C and issues through the perforations in the distributor 33 and its arms 40 so that the dye-liquor will contact with all portions of the material to be dyed. The dye-liquor impregnates the compressed material to be dyed and rising to the top of the vat A flows into the conduit 29 and returns through the suction pipe D to the pump B to be again forced through the supply pipe C to the dye vat. This circulation is continued as long as desired, whereupon the dye-liquor is drawn off and a rinsing liquor circulated through the machine in a similar manner.

Owing to the fact that the distributor 33 with its radiating hollow arms 40 extends to practically all parts of the liquor receiving chamber a the dye-liquor will rise under the pressure afforded by the pump B, passing through all portions of the compressed dye-

ing material and will overflow in substantially the same quantities over all portions of the side wall of the dye vat into the conduit 29, wherein by reason of the inclined bottom 31 it will rapidly flow toward the discharge opening 32 and be quickly drawn off by the suction effected by the pump B through the pipe D. Thus it will be apparent that all the elements of applicant's machine coöperate to insure a complete and efficient circulating system, which produces a uniform flow of the liquor through all portions of the dyeing chamber. By allowing the dye-liquor to be quickly and readily drawn off on all sides of the vat, the resistant pressure within the dye-vat is relieved and the dye-liquor is enabled to circulate uniformly through practically all portions thereof. Again the dye-liquor being forced into the dye-vat by the pump B is enabled to penetrate the compressed dyeing material by virtue of its initial pressure without having to overcome the weight and pressure of a heavy body of liquor resting upon the dyeing material. Provision is made for the reversal of the direction of flow of the dye-liquor, the supply pipe C becoming the return or suction pipe and the return pipe D the supply pipe for conducting the dye-liquor to the vat A. The valves *c* and *c'* are adjusted to allow the dye-liquor to enter the pump B through the pipes C and *C*², and the valves *d*, *d'* and *d*² are adjusted to allow the dye-liquor to be forced by the pump through the pipes *C*³, *D*⁴, *D*⁵ and D into the conduit 29, overflowing therefrom into the dye-vat A, permeating the dyeing material therein, and falling into the chamber *a*, from which it is withdrawn through the distributor 33 and pipes C and *C*². After the various steps in the dyeing process have been completed the clamps 26 are swung to the outside of the vat and the compression plate 10 is removed by the hoist 28 or other suitable means. The false bottom plate 11 and the material carried thereon is then removed by said hoist or other suitable means and the material deposited wherever desired.

While the present embodiment herein shown is well adapted to accomplish the several purposes of my invention, it is to be understood that the invention is not restricted thereto but is capable of many changes, modifications, and variations within the scope of the subjoined claims.

In practice suitable heating means are preferably embodied in the apparatus, but it is not deemed necessary to illustrate the same herein. Such heating means may be the coiled or other pipes ordinarily employed, or may be a suitable heating chamber interposed between the dye vat and the pump, as, for example, that illustrated in my co-pending application Serial No. 65 553,469 filed of even date herewith.

Having now described the invention what I believe to be new and desire to secure by Letters Patent, is:-

1. In a dyeing apparatus, a vat having a liquor-receiving chamber, a dyeing chamber and a discharge chamber, and having substantially entirely around its discharge chamber a relatively shallow conduit which has substantially unrestricted communication therewith, said vat also having a perforated plate between its dyeing chamber and the liquor-receiving chamber and a second perforated plate between said dyeing chamber and the discharge chamber, and means for supplying liquor to the liquor-receiving chamber and withdrawing it from said shallow conduit. 70 75 80

2. In a dyeing apparatus, a vat having a liquor-receiving chamber, a dyeing chamber and a discharge chamber, and having substantially entirely around its discharge chamber a relatively shallow conduit which has substantially unrestricted communication therewith, said vat also having a perforated plate between its dyeing chamber and the liquor receiving chamber and a second perforated plate between said dyeing chamber and the discharge chamber, and means for circulating liquor through the vat, comprising a suction pipe having connection 95 with said shallow conduit and a supply pipe having a head provided with a plurality of arms each having a series of outlets in the liquor-receiving space. 85 90 95

3. In a dyeing apparatus, a vat having a liquor-receiving chamber, a dyeing chamber and a discharge chamber, and having around its discharge chamber a means for receiving the liquor from the latter, the discharge chamber having substantially unrestricted communication with said means over its top, said means having a bottom which extends substantially around the vat and in such proximity to the top of the overflow space as to provide a relatively shallow conduit, 100 105 110 said conduit having an aperture for the flow of liquor therefrom and having its bottom wall inclined to said aperture to induce a more rapid flow of the liquor therein, and means for the supply of liquor to the liquor-receiving chamber of the vat. 115

4. A dyeing apparatus, comprising a vat having a liquor-receiving chamber and a chamber adapted to receive material in bulk to be treated; a perforated plate arranged between said chambers; a second perforated plate opposite to the first-mentioned plate and adapted to compress the material between it and the latter; and a distributor having a head and a series of angularly disposed arms, the said arms extending in various directions radially from said head and having their longitudinal sides provided with series of apertures arranged to discharge the liquor into said liquor-receiving 120 125 130 135 140 145 150

chamber, said vat having at the outlet side of the second perforated plate provision for the outflow of the liquor substantially entirely around the vat.

5. A dyeing apparatus, comprising a vat having a liquor-receiving chamber, a chamber adapted to receive material in bulk to be treated, a perforated plate between said chambers, a liquor-discharging chamber and a perforated compression plate between the treating chamber and the discharging chamber: a relatively shallow conduit extending substantially entirely around the discharging chamber and having substantially free communication therewith throughout substantially the entire length thereof: a distributor comprising a head and radial arms extending from the head and having their longitudinal sides provided with series of apertures arranged to discharge the liquor into the liquor-receiving chamber: and liquor-circulating means adapted to supply the liquor to the head and arms and withdraw the same from the conduit.

20 6. A dyeing apparatus comprising a vat having a liquor-receiving chamber and a chamber adapted to receive material in bulk to be treated; a perforated plate arranged between said chambers: a second perforated plate arranged opposite to the first-mentioned plate and adapted to compress the material between it and the latter; and a distributor having a head and hollow perforated arms radiating from the head, said arms being arranged to discharge liquor into the liquor-receiving chamber and having a solid portion and being adjustably mounted to present either the perforations or the solid portion toward the dyeing chamber.

25 7. A dyeing apparatus comprising a vat; a removable perforated plate arranged in said vat above the bottom of the latter and forming with said bottom a liquor-receiving chamber; a distributor arranged in said chamber and comprising a head and hollow radial arms, each of said arms having a perforated portion and a solid portion and being adjustably connected to said head so that it may be turned to present either its perforated portion or its solid portion toward said plate; a perforated compression plate arranged in the vat above the first mentioned plate and adapted to compress the material between it and the latter and means for supplying the distributor with liquor under pressure and for withdrawing the liquor from the discharge portion of the vat.

30 8. A dye vat comprising a dyeing chamber and a liquor-receiving chamber having communication with the dyeing chamber, said liquor-receiving chamber being provided with hollow radial arms each having a perforated portion and a solid portion, said arms being adjustable to present either the

perforated portions or the solid portions thereof toward the dyeing chamber.

9. A dye vat provided with a dyeing chamber and having a distributor comprising a head having a perforated wall presented toward the said dyeing chamber and hollow arms which radiate from the head and are each provided with a series of perforations.

10. A dye vat provided with a dyeing chamber and having a distributor comprising a multi-lateral head having a perforated wall presented toward the said dyeing chamber and a hollow perforated arm secured to each of its sides and extending radially from the head.

11. A dye vat comprising a liquor-receiving chamber, a dyeing chamber and a perforated plate between said chambers, in combination with a distributor having a multi-lateral head provided with a perforated wall presented toward the dyeing chamber and a hollow perforated arm connected to each of its sides and extending into the liquor-receiving chamber, each of said arms having a solid portion and a perforated portion and being adapted to be turned to present either its solid portion or perforated portion toward the dyeing chamber.

12. A dye vat, a perforated plate arranged in said vat and spaced from the bottom thereof, a distributor mounted in the space between the bottom of the vat and said plate, said vat having an opening in its bottom, a supply pipe, and a coupling member having a conduit through which the distributor is connected with the supply pipe, said conduit being of less diameter than the opening in the bottom of the vat and said coupling member having a flange or plate adapted to cover said opening.

13. A dye vat having an opening in its bottom, a perforated plate arranged in said vat in a spaced relation with said bottom, a distributor mounted in the space between said bottom and plate, said distributor comprising a head which is of less diameter than the opening in the bottom and hollow perforated arms extending radially from said head, a supply pipe and a coupling member having a conduit through which the distributor is connected with the supply pipe, said conduit being of less diameter than the opening in the bottom of the vat and said coupling member having a flange or plate adapted to cover the opening.

14. In an apparatus for dyeing material in bulk and which material is held under compression while being dyed, a vat having a dyeing chamber and a liquor-receiving chamber, said liquor-receiving chamber being of lesser internal diameter throughout than the dyeing chamber, the vat having at the junction of the two chambers

- a continuous shoulder which forms a seat, combined with a removable plate having a part which engages said seat and also having a flange which extends substantially 5 to the bottom of the liquor-receiving chamber and whose outer surface is in close proximity throughout its length to the wall of the vat, means for supplying liquor to said chamber, the removable plate having its part bounded by said flange provided with perforations through which the liquor flows directly to the material in the dyeing chamber, and means for compressing the material against the first-mentioned plate, the latter 10 means comprising a second perforated plate movably mounted in the vat in a spaced relation with the first perforated plate and means for holding the second plate in its adjusted position.
- 15 15. In combination with a dye vat, a perforated inner plate spaced from the bottom of said vat and a perforated compression plate spaced from the first mentioned plate, said compression plate being formed of a series of concentric webs extending from the perforated bottom thereof and being of gradually decreasing height from the innermost web to the outermost web, said outermost web being disposed near the outer edge 20 of the compression plate and provided with an outwardly extending portion of gradually reduced thickness which reinforces the edge of the plate, said plate being also provided with a series of radially extending ribs which connect said webs with each other, the ribs extending from the innermost web to the outermost web.
- 25 16. A dye vat provided with a perforated bottom plate and a perforated compression plate, the latter having webs and radiating ribs projecting from one of its surfaces, the outermost of said webs being disposed inside the plane of the edge of the plate and provided with a beveled portion extending therefrom to the edge of the plate and having pockets cut therein at intervals, and compressing elements extending over the edge of the vat and bearing against the 30 pockets in said tapered portion.
- 35 17. A dye vat provided with a perforated bottom plate and a perforated compression plate, the latter having webs and radiating ribs, projecting from one of its surfaces, the outermost of said webs being disposed inside the plane of the edge of the plate and provided with a beveled portion extending therefrom to the edge of the plate, having pockets cut therein at intervals, inwardly 40 extending perforated braces reinforcing said outermost web opposite each of said pockets, and compressing elements extending over the edge of the vat and bearing against the pockets in said tapered portion.
- 45 18. In a dyeing machine, a circulating pump, a supply pipe leading therefrom, a dye vat having a liquor receiving chamber, a dyeing chamber, and a discharge chamber therein, perforated plates arranged between said chambers, a distributor having radial arms arranged in said liquor receiving chamber and connected to the supply pipe, a relatively shallow conduit completely encircling the discharge chamber of the vat and communicating with the latter throughout its length, and a return pipe connecting said conduit with the pump.
- 50 19. In a dyeing machine, a circulating pump, a supply pipe leading therefrom, a dye vat having a liquor receiving chamber, a dyeing chamber, and a discharge chamber therein, perforated plates arranged between said chambers, a distributor having radial arms arranged in said liquor receiving chamber and connected to the supply pipe, a relatively shallow conduit completely encircling the discharge chamber of the vat and communicating with the latter throughout its length, and a return pipe connecting said conduit with the pump.
- 55 20. In a dyeing machine, a circulating pump, a supply pipe leading therefrom, a dye vat having a liquor receiving chamber, a dyeing chamber, and a discharge chamber therein, perforated plates arranged between said chambers, a distributor provided with radially-disposed arms having a perforated and a solid portion arranged in said liquor-receiving chamber and connected to the supply pipe, a relatively shallow conduit completely encircling the discharge chamber of the vat and communicating with the latter throughout its length, said conduit having an aperture and its bottom inclined to said aperture, and a return pipe connecting said conduit with the pump.
- 60 21. A dyeing apparatus comprising a vat having a dyeing chamber; a removable plate arranged in said vat above the bottom of the latter and forming with said bottom a liquor-receiving chamber, said plate also forming the bottom of the dyeing chamber and having perforations through which the liquor flows directly to the material in the dyeing chamber; a distributor arranged in said chamber and comprising a head and hollow radial arms, each of said arms having a perforated portion and a solid portion so as to project the liquor in a desired direction; a perforated compression plate arranged in the vat above the first mentioned plate and adapted to compress the material between it and the latter and means for supplying the distributor with liquor under pressure and for withdrawing the liquor from the discharge portion of the vat.
- 65 22. A dye vat, comprising a liquor receiving chamber and a dye chamber, said vat having an apertured bottom, a perfor-

- ated plate separating its said chambers from each other, a distributer mounted in the liquor-receiving chamber and comprising a head having a perforated wall portion presented toward the dyeing chamber and perforated arms connected with and radiating from said head, a supply pipe and a coupling member adapted to cover the aperture in the bottom of the vat and provided with a conduit which connects the distributer with the supply pipe. 40
- 5 23. In dyeing apparatus, a vat having a liquor-receiving chamber, a dyeing chamber and a discharge chamber, a conduit arranged around the upper portion of said vat and adapted to receive overflow from the discharge chamber thereof, means for withdrawing dye-liquor from said conduit, a distributer provided with means to discharge the liquor into the liquor receiving chamber, means to space the material to be dyed from said distributer, a compression plate arranged in the upper portion of the vat and having means for the passage of liquor, said dyeing chamber comprising the space between the compression plate and said spacing means, means for raising and lowering said compression plate, and means for holding it in an adjusted position. 55
- 10 24. In dyeing apparatus of the type herein set forth, a vat having a liquor receiving chamber, a dyeing chamber and a discharge chamber, means to receive overflow from the latter and means to withdraw the dye-liquor from said overflow-receiving means, means for admitting liquor to said liquor-receiving chamber, the latter being of lesser internal diameter throughout than said dyeing chamber, a plate separating the dyeing chamber 60
- 15 25. In dyeing apparatus, a vat having a conduit surrounding the upper portion of its side wall, a portion of said wall forming part of the conduit, said wall being enlarged at the lower portion thereof to form a shoulder whereby the lower portion of the vat is of lesser diameter than that portion of the vat above said shoulder, means for admitting dyeing liquor to said lower portion of the vat, and a plate adapted to rest upon said shoulder, said plate being provided with perforations for the passage of liquor therethrough, but not in the region thereof near its outer periphery, whereby on account of the lesser diameter of said liquor-receiving chamber and the arrangement of the perforations on said plate liquor passing through the latter will not be projected toward the wall of the chamber above said plate forming the dyeing chamber. 65
- 20 30 35
- In testimony whereof I have hereunto set my hand in presence of two subscribing witnesses.
